UNITED STATES PATENT OFFICE.

EDWARD W. BING, OF PHILADELPHIA, PENNSYLVANIA.

MACHINE FOR MAKING SUPPOSITORIES.

SPECIFICATION forming part of Letters Patent No. 244,030, dated July 12, 1881.

Application filed May 16, 1881. (No model.)

To all whom it may concern:

Be it known that I, EDWARD WILLIAM BING, a subject of Great Britain, residing in the city and county of Philadelphia, State of Pennsylvania, have invented a new and useful Improvement 5 in Machines for Making Suppositories, which improvement is fully set forth in the following specification and accompanying drawings, in which—

10 Figure 1 is a perspective view of the machine embodying my invention. Figs. 2 and 3 are plan views of detachable trays thereof. Fig. 4 is a plan view with the trays in position. Fig. 5 is a transverse vertical section in line 15 *xx*, Fig. 1, the trays being added.

Similar letters of reference indicate corresponding parts in the several figures.

My invention consists of a machine for making suppositories which is simple, inexpensive, 20 and durable, and operates quickly, reliably, and uniformly, as will be hereinafter fully set forth.

Referring to the drawings, A represents the bed-plate of the machine, the upper face of 25 which is depressed or grooved longitudinally, the base of the groove being somewhat inclined, as at *a*, and curved or bent upwardly, as at *b*.

B represents the roller plate or slide, which is formed with longitudinally-extending 30 pending flanges *c*, which, when said plate is fitted on the bed-plate, overlap the side walls *d d'* of the latter, and serve to guide the roller-plate and retain it in position.

It will be noticed that the wall *d* of the bed- 35 plate is higher than the wall *d'*. Consequently the inner face of the roller-plate is inclined in the direction the reverse of the inclined portion *a* of the base, thus forming a tapering space between the bed-plate and roller-plate, 40 as shown in Figs. 1 and 5.

The mass from which the suppository is to be formed is properly divided, and one or more of the parts placed on the bed-plate A, in the groove thereof, properly dusted. The roller- 45 plate B is now located over the bed-plate and moved to and fro with a gradually-increasing

pressure until the suppository is properly shaped, after which it is removed.

In order to produce suppositories of smaller size I employ a tray, C, and for a smaller size 50 a tray, D, and may employ still smaller ones, if desired. The trays C D have each hooks or hooked ends *e e*, which are adapted to engage with the wall *d* of the bed-plate, as more clearly shown in Fig. 4. The tray C is placed 55 in the groove of the bed-plate and reduces the space between the latter and the roller-plate, and the tray D is placed on the tray C, thus further reducing said space, whereby it is evident that smaller masses must be employed 60 and smaller suppositories will be produced, it being noticed that the contour of the upper faces of the trays C D accords with the upper face of the bed-plate, the only variation being 65 in the size, as has been stated.

The trays, owing to their hooks or hooked ends *e*, may be readily located and reliably retain their position, especially during the manipulations or movements of the roller-plate B.

The device or machine will be found to be 70 strong and durable and render efficient service, all molds and complicated and expensive parts being dispensed with, and freezing of the suppository while setting it avoided.

Having thus described my invention, what 75 I claim as new, and desire to secure by Letters Patent, is—

1. The bed-plate and roller-plate having their inner faces form a tapering space between them, substantially as and for the purpose 80 set forth.

2. The bed-plate provided with removable trays C D, substantially as and for the purpose set forth.

3. The suppository-machine provided with 85 removable trays, which are formed with hooks adapted to engage with the bed-plate, substantially as and for the purpose set forth.

EDWARD WM. BING.
